UNITED STATES PATENT OFFICE.

ALFRED DUNHILL, OF LONDON, ENGLAND.

GAME APPARATUS.

Application filed September 28, 1920. Serial No. 413,396.

To all whom it may concern:

Be it known that I, ALFRED DUNHILL, a subject of the King of Great Britain and Ireland, residing at London, England, have 5 invented certain new and useful Improvements in Game Apparatus, of which the following is a specification.

This invention relates to game apparatus and refers to that type of such apparatus in 10 which moving figures or objects representing, for instance, horses, boats, tanks or the like are provided, drawn by means of cords under the control of the players, in order to constitute a race game.

15 My present invention is designed to provide an improved apparatus of the class in question, enabling considerable scope to be obtained for the skill and dexterity of the players.

20 According to the general form of carrying out the invention I provide a rod or spindle suitably supported in standards or bearings at appropriate distances and adapted to be rotated by means of a handle, motor or other 25 suitable device.

The spindle is provided at appropriate intervals with means for attaching a cord, one for each model and player.

I further provide for each player, a guide, 30 which may be pivotally mounted, so that it has scope for a limited lateral movement and which is adapted to guide or control the cord as it rolls or winds upon the spindle, the object of each player being to so control 35 his cord that the thickness of the roll or coil formed on the spindle increases with the maximum rapidity, thus causing his model to be drawn in more rapidly than those of the other players, thus winning the game.

40 In one particular method of carrying out my invention I provide a box like fitting of suitable length and shape to be rested or supported at the edge of the table. The spindle is mounted in this box or casing, 45 being supported by means of bearings at the end and by intermediate bearings where its length renders this desirable. The spindle is provided at appropriate distances apart, with eyelets and a cord is knotted into each 50 eye, or any other suitable method of attachment may be provided of a kind ensuring that the cord will be drawn in, as the spindle is rotated.

The model to be moved is attached to the 55 free end of the cord in the ordinary way.

Mounted opposite to each of the cords

upon a suitable pivot or standard is a wire or like device provided at one end with an operating ring or handle and prolonged at the other end into a loop eye or its equivalent adapted to engage the cord at some little distance in front of the spindle.

In this way, as previously stated, each player can exercise his skill in endeavouring to make the cord as far as possible roll or 65 coil upon itself, thus forming a coil of minimum width and maximum diameter.

The handle of the spindle may be operated by a participating player, an independent player or by means of a motor.

In order that the invention may be readily understood reference is made to the accompanying drawings, in which,

Fig. 1 is a perspective view of the apparatus.

75 Fig. 2 is a part sectional view, to an enlarged scale, of the guiding means for the cord or line connected to the model and,

Fig. 3 is a sectional view, showing one 80 method of rotating the spindle on which the cords or the like are wound.

The apparatus comprises a box or casing *a* of suitable shape and size, the top of which has hinged thereto a lid or cover *b* whilst one of the sides *c* is preferably hinged to 85 the base of the box, as shown in Fig. 1. Suitable means are provided for retaining the lid *b* and the hinged side *c* in their closed position.

Extending longitudinally within the box 90 is a spindle or shaft *d* rotatable in suitable bearings in the end walls *e*, *e*¹ of the box and also preferably in the division walls or partitions *f* of the box. The spindle *d* is provided at appropriate distances apart with 95 eyelets or the like *d*¹ into each of which a cord or the like *g* is knotted so as to be wound or coiled thereon when the spindle is rotated. To the opposite end of the cord is attached a model which may be made to represent a horse, as at *h* or any other device.

One end of the spindle *d* is provided with a cross pin *d*² with which a cranked handle *k* is engaged.

The rear wall *a*¹ of the box or casing is 105 preferably provided with recesses *a*² at its top edge in which are pivotally mounted a guiding device, consisting of a rod or bar *m* having thereon, intermediate its ends a pin *m*¹ which engages a corresponding hole *a*³. 110 One end of the bar *m* is shaped in any suitable manner to constitute a handle whilst

the opposite end is formed with or has attached thereto a loop, or eye piece n engaging the cord at a point in front of the spindle d . The recesses a^2 are located at a point 5 immediately behind the eyelets d^1 and are of such size and shape as to permit of limited rotation of the rods m about the pins m^1 so that by manoeuvring the rods in an appropriate manner when the spindle is rotated 10 it is possible to reduce the width of the coil or winding of the coil of cord upon the spindle to the minimum extent thus causing the diameter of the coil to be correspondingly increased and resulting in the model moving 15 towards the spindle at a greater speed.

In the construction shown in the drawings, the lid or cover h is adapted to be fixed in a position in which it extends below the lower or bottom edge of the box, so as to enable 20 the whole apparatus to be easily retained in position against the edge of the table or other surface o .

The operation will be readily understood. The box or casing is placed in position as 25 shown in Fig. 1 and the model of each player is moved outwardly to its maximum extent. The spindle d is now rotated either by one of the players or by an independent person or if desired by mechanical or other means. 30 Each player manipulates the guiding device of his model, so as to cause the cord or the like to wind onto the spindle, thus increasing the diameter of the coil and increase the speed of travel of the model.

35 When not in use the guiding devices m and the models h together with the handle h may be enclosed in the box and the latter closed in the usual manner.

In some cases a separate device may be 40 provided, one for each player, the spindle being mounted upon a box or upon suitable standards on a base plate, standing on or attached to the edge of the table, the player operating the spindle by means of a handle 45 with one hand, whilst he manipulates the pivoted guide for his cord with the other hand.

In some instances, where the spindle is mounted in a box or casing, such box or casing 50 may be provided with a hinged or loose cover which can be turned back or otherwise placed so that it comes under the body of the box, and a flange or projection may be provided constituting part of the box, when 55 closed, and adapted when the box is opened to rest against the edge of the table to prevent the box moving.

In all cases where found desirable screw, 60 spring or other clamps or appropriate means may be furnished for steadyng the devices or holding them in position.

It will be understood that the particular

method of carrying out the invention may be varied considerably without departing from the principle thereof.

What I claim and desire to secure by Letters Patent of the United States of America is:—

1. Game apparatus of the type described comprising a box, a rotatable spindle journaled thereon, a plurality of cords attached at one end at spaced intervals apart to said spindle and each attached at the other end to a model, means for rotating said spindle, guiding devices for each of said cords, comprising pivoted bars, one end of each bar engaging one of said cords, adjacent said spindle, and the opposite end constituting a handle for manipulation.

2. Game apparatus of the type described comprising a box having a movable lid and a movable wall, a spindle supported for rotation in said box, means for rotating said spindle, spaced eyelets on said spindle, cords attached to each of said eyelets, models attached to the ends of said cords, guiding means for each of said cords, each of said guiding means consisting of a bar pivoted intermediate its ends, one end having means for engaging the cord adjacent said spindle while the other end constitutes a handle, and means for limiting the movement of each of said bars about its pivot.

3. Game apparatus comprising a box, having a hinged lid adapted to be turned to a position to locate the box against the edge of a playing surface, means for securing said lid in the open position, a spindle supported for rotation in said box, cords attached to said spindle at spaced intervals apart, models attached to the ends of said cords, guiding means for each of said cords, said guiding means consisting of pivotal bars each having a handle at one end and adapted to engage the cord at the other end, and means for limiting the movement of said bars.

4. Game apparatus comprising a box having a movable lid, a spindle mounted for rotation in said box, a series of cords attached to a model at one end, the points of connection to said spindle being located at spaced intervals apart, the said box being provided with slots in the adjacent wall of said box, opposite to the points of attachment of each of said cords to said spindle, a bar pivotally mounted in each of said slots so as to have limited movement therein, means at one end of said bars for connection to the adjacent cord, and handles at the opposite ends of said bars, substantially as and for the purposes set forth.

In testimony whereof, I affix my signature,
ALFRED DUNHILL.
